UNITED STATES PATENT OFFICE.

LOUIS BIERACH, OF MILWAUKEE, WISCONSIN, ASSIGNOR OF ONE-HALF TO
KARL MUELLER, OF MILWAUKEE, WISCONSIN.

LETTER-PRESS-COPYING CLOTH AND FRAME.

SPECIFICATION forming part of Letters Patent No. 707,753, dated August 26, 1902.

Application filed December 4, 1901. Serial No. 84,597. (No model.)

To all whom it may concern:

Be it known that I, LOUIS BIERACH, residing at Milwaukee, in the county of Milwaukee and State of Wisconsin; have invented a new and useful Improvement in Letter-Press-Copying Cloths and Frames, of which the following is a description, reference being had to the accompanying drawings, which are a part of this specification.

10 My invention has relation to improvements in letter-press-copying cloths and frames.

One of the objects of the invention is to provide a construction wherein the copying-cloth is always maintained in a stretched or taut

15 condition.

A further object resides in the provision of a construction whereby the copying-cloth when worn or otherwise impaired may be readily removed from the frame and a new

20 cloth substituted therefor.

A still further object resides in the provision of a construction whereby the length of the frame may be readily adjusted, so as to suit copying-press books of different sizes.

25 With the above and other incidental objects in view the invention consists of the devices and parts or their equivalents, as hereinafter set forth.

In the accompanying drawings, Figure 1 is an elevation of my invention. Fig. 2 is an edge view of the arms 7 and of the copying-cloth. Fig. 3 is an elevation of a modified form of construction wherein the frame is adjustable. Fig. 4 is an edge view of Fig. 3, and Fig. 5 is a

35 cross-section on the line 5-5 of Fig. 4.

Referring to the form of construction illustrated in Figs. 1 and 2, the frame consists of a main member 6 and the two parallel arms 7, projecting from said main member, the 40 whole forming a substantially U-shaped frame. This frame may be made of any desirable material, although thin and light flat metal of such character as to resist corrosion and preferably possessing a slight degree of elasticity or spring will probably be found the

45 most desirable in practice.

The copying-cloth, which may be of cotton or any other suitable material, is indicated by the numeral 8. The end edges of this cloth

50 are secured to the projecting arms 7 in such manner that the cloth will be stretched and

held taut, which, as is well understood, is quite desirable in the successful copying of letters. I also prefer to removably secure said end edges on the arms 7 in order to provide for the cloth after it has become worn or otherwise impaired being readily removed and a new cloth substituted therefor. To provide for this, I turn over and stitch said end edges of the cloth so as to form loops 9, 55 which loops receive therein the arms 7 and are of sufficient size to permit them to be readily withdrawn off the arms.

It will be evident from the construction thus far explained that I provide a most simple, cheap, and efficient form of letter-press-copying cloth and frame and one at the same time in which the cloth is always maintained taut or stretched. The length of the arm 7 is such that when the device is arranged between the leaves of a copying-press book the main member 6 will lie parallel with and on the outside of the outer side edges of the leaves, and the distance apart of the arms 7 is such that said arms will lie parallel with 70 and on the outside of the opposite end edges of the leaves. In this manner only the copying-cloth is disposed between the leaves, whereby the frame is prevented from being injured by the compression effected by the 75 press, and at the same time the book is permitted to be closed perfectly flat, so as to be capable of being subjected to equal pressure throughout.

It may be found desirable in practice to 80 provide for the frame being adjustable or extensible in length, so as to adapt it to different sizes of letter-press books. This may be accomplished by making the main member 6 of two parts adjustably secured together. 85 In Figs. 3, 4, and 5 I show the preferred construction for adjustably holding the sections of the main member together. In these figures one section of the main member is indicated by the numeral 6' and the other section by the numeral 6". These sections are shown in overlapping engagement, and one is provided with a series of apertures 10 and the other with a series of apertures 10', and two of the apertures of the respective series may 90 be brought into alignment or registration by sliding the sections upon each other. The

apertures 10 of the sections 6' are plain or unthreaded, while the apertures 10' of sections 6' are threaded. (See Fig. 5.) A small screw 11 is adapted to be passed through the registering apertures, the extremity only of said screw being threaded so as to engage with the threads of the aperture 10'. In order to form guides for the sliding of one section of the main member upon the other, I prefer that the 10 end of each of said sections shall be split and spread out laterally and thence bent around and beneath the other section, as indicated by the numerals 12 12.

While the above-described construction for 15 adjustably holding the sections of the main member together is the preferred means, yet I do not wish to be understood as limiting myself specifically thereto, inasmuch as it is obvious that any other desirable construction 20 for holding said sections adjustably together may be employed without departing from the spirit and scope of my invention. By providing for this adjustment it is obvious that the length of the frame can be readily adjusted so as to suit different sizes of letter- 25 press books, and all that will be necessary will be to have on hand a supply of different lengths of the cloth. This adjustable feature may also be found useful merely for the purpose of placing the cloth under additional 30 tension or stretching if from any cause said cloth may sag or become loose.

What I claim as my invention is—

1. In a letter-press-copying cloth and frame, 35 the combination with a copying-cloth, of a frame comprising a main member and two arms extending in the same direction and at angles from opposite ends of the main member, said arms having the opposite end edges 40 of the cloth secured thereto, and the cloth drawn tight thereby, the length of the arms being such that the main member will lie parallel with and outside of the outer side edges of the leaves of the copying-press book, 45 when the device is applied between said leaves, and the distance apart of the arms being such that said arms will lie parallel with and outside of the opposite end edges of the leaves of the book.
2. In a letter-press-copying cloth and frame, 50 the combination with a copying-cloth, of a frame comprising a main member and two arms extending in the same direction and at angles from opposite ends of the main mem-

ber, said arms having the opposite end edges 55 of the cloth removably secured thereto and the cloth drawn tight thereby, the length of the arms being such that the main member will lie parallel with and outside of the outer side edges of the leaves of the copying-press 60 book, when the device is applied between said leaves, and the distance apart of the arms being such that said arms will lie parallel with and outside of the opposite end edges of the leaves of the book. 65

3. In a letter-press-copying cloth and frame, the combination with a copying-cloth having its opposite end edges provided with loops, of a frame comprising a main member and two arms extending in the same direction and at 70 angles from opposite ends of the main member, said arms adapted to have the end loops of the cloth removably fitted thereon and the cloth drawn tight thereby, the length of the arms being such that the main member will 75 lie parallel with and outside of the outer side edges of the leaves of the copying-press book, when the device is applied between said leaves, and the distance apart of the arms being such that said arms will lie parallel with 80 and outside of the end edges of the leaves of the book.

4. In a letter-press-copying cloth and frame, the combination of a frame comprising a main member consisting of two sections extensibly 85 fitted together, and each section having an arm extending therefrom at an angle, means for holding the sections of the main member in adjusted position, and a copying-cloth secured at opposite end edges of the arms. 90

5. In a letter-press-copying cloth and frame, the combination of a frame comprising a main member consisting of two sections slidably fitted together, and each section provided with apertures, any two of which may be 95 brought into registration, and each section also provided with an arm extending at an angle therefrom, a pin adapted to be fitted in the registering apertures to thereby hold the sections in adjusted position, and a copying-cloth secured at opposite end edges to the arm. 100

In testimony whereof I affix my signature in presence of two witnesses.

LOUIS BIERSACH.
